CONTROL OF HEAT ABSORPTION IN STEAM SUPERHEATER

Frederic I. Epley, Rockville Centre, N. Y., assignor to Combustion Engineering, Inc., New York, N. Y.

Application September 21, 1951, Serial No. 247,715

6 Claims. (Cl. 122—479)

The present invention relates to steam generators and particularly to an improved arrangement for the control of the final temperature of steam delivered by a superheater, or re heater, associated with a steam boiler.

Heretofore, various arrangements have been resorted to for regulating the temperature of steam delivered by a superheater associated with a steam generating boiler. Conventional arrangements include the use of dampers for by-passing around the superheater part of the gases flowing thereto from the boiler furnace or the use of a desuperheater. One such arrangement comprises the division of the superheater into several sections with a desuperheater located between them in the steam flow path in order to maintain the final steam temperature to a desired value. While both of these mentioned arrangements, and others not specifically described herein, have certain advantages, they also possess certain features which are sometimes considered objectionable.

The object of the present invention is to overcome the disadvantages entailed by the use of by-pass dampers or desuperheaters as well as to eliminate the expense attendant upon the provision and use of such apparatus for controlling superheat temperature. The present invention contemplates the control of the final temperature of steam from a superheater by controllably regulating the temperature of gases that flow over a heat absorbing section of the superheater or re heater. Specifically, this contemplates the employment of another heat exchanger, such as a part of an economizer, in a location where more or less heat may be abstracted from the gases before they flow over the heat absorbing elements of a superheater section or a re heater.

The invention will be best understood upon consideration of the following detailed description of an illustrative embodiment thereof when read in conjunction with the accompanying drawing in which the single figure is a diagrammatic illustration of a steam generating boiler equipped with a superheater and utilizing an economizer section to control superheat temperature in accordance with the invention.

In the drawing the numeral 10 designates a boiler furnace in which fuel is burned for the generation of steam as in the water tubes 12 aligning the walls of the furnace. The mixture of steam and water is discharged into a separator drum 14 and the separated steam flows through a conduit 16 to the inlet header 17 of the superheater which is located in a down pass 18 in communication at its upper end with the outlet of the furnace 10.

According to the invention the heat absorbing elements of the superheater that are located in the down pass 18 are divided into a primary section 20 and a secondary section 22 which are spaced apart in the direction of gas flow. In some installations an additional superheater section 23 may be provided between the outlet of furnace 10 and the down pass of furnace 18. In the arrangement shown, the steam to be superheated passes in counterflow first through the primary section 20 and then in series through the secondary section 22 from

which it is discharged into the preheater outlet header 24. Section 23 may follow the section 22 in series. Located in gas pass 18 between the primary section 20 and the secondary section 22 of the superheater is a heat exchanger which, in accordance with the invention, has its heat absorbing capacity controllably regulated so as to absorb more or less heat from the gases after they have passed over the secondary section 22 in order to predeterminedly regulate the temperature of gases that flow over the primary section 20 of the superheater.

Although various types of heat exchangers might be employed between the two sections 20 and 22 of the superheater an economizer is chosen for the purpose of illustration. The feed water for the boiler is provided by a supply line 25 that is divided into the branches 26 and 27 having valves 28 and 29 therein for regulating the apportionment of the feed water between a main economizer section 30 and another economizer section 32 which is positioned in the location between the primary section 20 and the secondary section 22 of the superheater. The heated water from the economizer sections passes through the pipe 33 into the steam and water drum 14. The water flow path through the economizer section 30 constitutes a by-pass around the control section 32. A thermostatic device 34 responsive to the temperature of steam in the superheater outlet header 24 is arranged to control the operation of the valve operating mechanisms 36 and 38 in conventional manner to operate the valves 28 and 29 so as to apportion the flow of feed water between the economizer sections 30 and 32 in such manner as to maintain a predetermined final steam temperature.

The section 22 (or 22 and 23) of the superheater has sufficient heat absorbing surface to give the required steam temperature at maximum capacity of the steam generating unit. There is then no need for obtaining heat from the section 20 of the superheater. To accomplish the elimination of a superheating effect in section 20 the economizer part 32 is made sufficiently large to reduce the gas temperature entering section 20 to the point where it would equal the saturated steam temperature entering the superheater.

On the other hand, when the load on the boiler is reduced, the gas temperature T_3 is reduced, thereby reducing the amount of heat that section 22 (or 22 and 23) may absorb. In order to maintain desired final steam temperature leaving the superheater outlet header 24, section 20 is made effective and this is done by reducing the amount of water flowing through the economizer section 32, even to the extent of eliminating the water flow completely. The diversion of the water is accomplished by means of the valves 28, 29 directing the flow of water to or away from the economizer section. It is of course important that the economizer section 32 be located in a gas temperature zone which will not be excessive at times when no water passes through the economizer tubes.

Thus, the steam temperature delivered by a superheater may be controlled by effectively controlling the difference between the gas temperature and steam temperature at the cold end of the superheater surface. The heat absorbing surface in section 22 (or 22 and 23) would be fixed so as to obtain the desired steam temperature at full load. The economizer surface 32 is made sufficient to reduce the gas temperature, T_2 , to the same level as the saturated steam temperature so as to render the surface in superheater section 20 ineffective. As the load diminishes, gas temperature, T_3 , becomes lower so as to require more superheater surface. At half load for example, the economizer surface 32, is made ineffective by bypassing water through the main economizer 30 so that superheater surface 20 becomes fully effective. Surfaces 22 (or 22 and 23) plus section 20 are sufficient to give full steam temperature at reduced loads.

The same principle can be applied to reheat boilers to control both primary and low pressure steam temperatures. In a boiler equipped with a reheat the latter might be mounted in the place of the primary section 20 of the superheater. The reheated steam temperature would then be controlled in the manner described above, as will be apparent, since a reheat is essentially a steam superheater but used for raising the temperature of steam from the primary section of a turbine before it continues to the secondary turbine.

What I claim is:

1. In fluid heating apparatus having a gas pass through which hot gases flow; superheater means including a superheater portion disposed in said pass; a fluid heater having heat absorbing elements disposed in said gas pass in a position upstream of said superheater portion with respect to the direction of gas flow in said pass; means for circulating a liquid to be heated through said heat absorbing elements with the heat absorbed by the liquid varying with its rate of flow through the heater; and means for controlling the flow of liquid through said heater, said means being regulated in response to the superheated steam temperature to increase and decrease the flow through the fluid heater in response to an increase and decrease respectively of this temperature whereby said means is effective to control the heat absorbed by said liquid so as to maintain a predetermined temperature at the outlet of said superheater.

2. In fluid heating apparatus having a gas pass through which hot gases flow; first and second steam superheater sections disposed in said pass and spaced apart in the direction of flow of gases therethrough; a fluid heater having heat absorbing elements disposed in said gas pass in a position between the two superheater sections; means for circulating a liquid to be heated through said heat absorbing elements with the heat absorbed by the liquid varying with its rate of flow through the heater; a by-pass conduit so connected as to divert part of the liquid to be heated around said heat absorbing elements; and means for regulating and apportioning the flow of liquid between said heater and said by-pass so as to maintain a predetermined steam temperature at the outlet end of the second superheater section.

3. In a boiler having steam generating elements and a fuel burning furnace and having an outlet from which the products of combustion flow through a gas passageway; a steam superheater connected to receive steam generated in said steam generating elements, said superheater being divided into first and second sections disposed in said passageway and connected for series flow of steam therethrough in the direction opposite to the flow of gases through said passageway; a heat exchanger having heat absorbing elements disposed in said gas passageway in a position between the two superheater sections; means for circulating a fluid to be heated through said exchanger elements; a by-pass conduit so connected as to divert part of the fluid to be heated around said exchanger elements; means for regulating and apportioning the flow of fluid between the said exchanger elements and said by-pass; and means responsive to the temperature of superheated steam at the outlet of said superheater operative to control said regulating means to increase and decrease the flow through the heat exchanger elements in response to an increase and decrease respectively of said temperature to maintain a predetermined superheated steam temperature.

4. In a boiler having a steam and water drum, steam generating elements connected thereto, and a fuel burning furnace having an outlet from which the products of combustion flow through a gas passageway; a steam superheater connected to receive steam generated in said steam generating elements, said superheater being divided into two series connected sections disposed in

said passageway in spaced apart relation with respect to the flow of gases through said passageway; a water heating economizer having heat absorbing elements disposed in said gas passageway in a position between the two sections of said superheater; means for circulating water through said economizer elements to said drum; a by-pass conduit so connected as to divert part of the water around said economizer elements; and means for regulating and apportioning the flow of water between the elements of said economizer and said by-pass operative to maintain a predetermined superheated steam temperature.

5. In a boiler the combination of a furnace into which fuel is introduced and burned, means associated with said furnace for generating steam, a gas passageway communicating with said furnace so that the combustion gases generated within said furnace are conveyed therethrough, means forming a part of the boiler for superheating the steam generated in said steam generating means by absorbing heat from said combustion gases and including a heat exchanger disposed within said gas passageway, means for supplying heated feed water to said boiler comprising an economizer including heat exchange means disposed in said gas passageway upstream of said superheater heat exchanger with respect to combustion gas flow, and heat exchange means disposed in said gas passageway downstream of said superheater heat exchanger with respect to combustion gas flow with said upstream and downstream heat exchange means being in parallel with respect to the flow of feed water, and means operative to adjustably proportion the flow of feed water between said upstream and downstream heat exchange means to vary the heat in said combustion gases available to heat the steam passing through said superheater heat exchanger.

35 6. In a boiler the combination of a furnace into which fuel is introduced and burned, means associated with said furnace for generating steam, a gas passageway communicating with said furnace so that the combustion gases generated within said furnace are conveyed therethrough, means forming a part of the boiler for superheating the steam generated in said steam generating means by absorbing heat from said combustion gases and including a heat exchanger disposed within said gas passageway, means for supplying heated feed water to said boiler comprising an economizer including heat exchange means disposed in said gas passageway upstream of said superheater heat exchanger with respect to combustion gas flow, and heat exchange means disposed in said gas passageway downstream of said superheater heat exchanger with respect to combustion gas flow with said upstream and downstream heat exchange means being in parallel with respect to the flow of feed water, the location of said upstream heat exchange means being such that it will not be deleteriously affected if the flow of feed water thereto should be completely stopped at and below a predetermined load on the boiler within the normal operating range of the boiler, and means operative to adjustably proportion the flow of feed water between said upstream and downstream heat exchange means to vary the heat in said combustion gases available to heat the steam passing through said superheater heat exchanger.
